(57) **CLAIM**

The ornamental design for a skate guard component, as shown and described.

DESCRIPTION

FIG. 1 is a perspective view of the design from the front, left side and top;

FIG. 2 is left side view of the design, the right side view being a mirror image thereof;

FIG. 3 is a perspective view of the design from the rear, left side and top;

FIG. 4 is a bottom view of the design; and,

FIG. 5 is left side view of the design, with a second skate guard component and connected to the skate guard component of the design, by means of a spring and two fasteners shown in broken lines.

The broken lines are for the purpose of illustrating portions of the article that form no part of the claimed design. The second skate guard component, spring and fasteners shown in broken lines in FIG. 5 are environmental and also form no part of the claimed design.
